UNITED STATES PATENT OFFICE.

FLORENCE C. BIGGERT, JR., OF ALLEGHENY, PENNSYLVANIA, ASSIGNOR TO UNITED ENGINEERING & FOUNDRY COMPANY, OF PITTSBURG, PENNSYLVANIA, A CORPORATION OF PENNSYLVANIA.

MANIPULATOR FOR ROLLING-MILLS.

No. 893,429.

Specification of Letters Patent.

Patented July 14, 1908.

Application filed June 28, 1907. Serial No. 381,228.

To all whom it may concern:

Be it known that I, FLORENCE C. BIGGERT, Jr., of Allegheny, Allegheny county, Pennsylvania, have invented a new and useful 5 Manipulator for Rolling-Mills, of which the following is a full, clear, and exact description, reference being had to the accompanying drawings, forming part of this specification, in which—

10 Figure 1 is a plan view partly broken away of a manipulating mechanism embodying my invention; Fig. 2 is a side view of the same with one of the table rollers in dotted lines; Fig. 3 is an enlarged view, partly diagrammatic of the working parts of the manipulator; Fig. 4 is a section on the line IV—IV of Fig. 1; and Figs. 5 and 6 are detail views of the tilting lifter arm.

15 My invention has relation to manipulators for rolling mills, and is designed to provide a manipulator for edging up billets or blooms on the roll table, and also moving them into line with the proper roll pass in transferring them from one pass to another.

20 A further object is to provide a manipulator of this character which shall be simple in its construction and operation, in which the entire work of the manipulator can be accomplished by a single motor, and in which 25 means are provided for holding the billet or bloom in its edged position.

25 My invention will be best understood by reference to the accompanying drawings which will now be described, premising, however, that various changes may be made in the details of the constructions and arrangement, by those skilled in the art, without departing from the spirit and scope of my invention.

30 The numeral 2 designates a suitable carriage which is mounted to reciprocate transversely of the roll table between two of the rolls 3.

35 4 designates a suitable bed frame having 45 guides 5 in which the base of the carriage 2 is mounted to move.

40 6 designates a rock shaft which is mounted transversely in bearings on the carriage 2, and to which is keyed or otherwise rigidly 45 secured a tiltable lifter arm 7, (shown in detail in Figs. 5 and 6). Projecting upwardly from the shaft 6, and preferably integral with the lifter arm 7, are the two parallel 50 arms 8 which are connected by the two parallel

55 links 9 with a cross head or slide 10 which is mounted for reciprocation on a suitable base 11, and to which is connected a piston rod 12 of a hydraulic or power cylinder 13 of the usual double acting type. Attached to the carriage 2 is a friction bar 14 whose end 60 portion extends through a suitable friction clamp 15, the action of which can be adjusted by means of springs 16 and nuts 16^a.

65 Pivottally mounted in and between the two arms 8 is an arm 17 in which is journaled a roller 18 which lies above the lifter arm 7. The arm 17 has an extension 19 below its pivot provided with a counterweight 20 and carrying a roller 21 which is adapted to travel in engagement with a cam surface 22 on the 70 carriage 2, being held against such surface by the counterweight 20. The cam surface 22 has, at its lower end, a depression 22^a, the purpose of which will presently appear.

75 The lifter arm 7 is normally below the level of the rolls 3, as shown in Figs. 2 and 4, and can be brought underneath a billet or bloom, in the manner indicated in these figures, by moving the carriage 2 by means of the motor 13. When it is desired to edge up the billet 80 or bloom, power is admitted to the cylinder 13, in the direction to actuate the arms 8 to elevate the lifter 7 into contact with the billet or bloom, and turn it upwardly and over 85 into edge position. During this movement of the lifter arm, the roller 21 travels downwardly along the cam surface 22, the roller 18 bearing lightly against the billet or bloom and steadyng its movement to prevent it 90 from falling over beyond its edge position. When the billet or bloom has been raised to its edge position, the roller 21, or the end of the arm in which the roller is journaled engages with the depression 22^a. Up to this 95 time, the friction exerted on the bar 14 has been sufficient to prevent movement of the carriage 2. As soon, however, as the roller engages the cam depression 22^a further movement of the tilting arm 7 is prevented, and 100 the further operation of the motor causes said carriage to move bodily, thereby transferring the bloom to the desired position on the roll table, as indicated in dotted lines in Figs. 2 and 3. During this transfer movement, the billet is steadied by the roller 18, and is held in its edge position until it enters 105 the roll pass.

The advantages of my invention result from the simplicity of the construction, and from the fact that the entire work of edging up and transferring the billet can be performed by a single motor. The parts are few in number and of such character as to efficiently withstand the work to which they are subjected.

What I claim is:—

- 10 1. A manipulator having a movable support, a lifter mounted on the support, an actuating motor, connections between the motor and the lifter, and connections between the lifter and its support whereby the actuation of the motor will first actuate the lifter to turn the bloom or blank, and will then impart a transfer movement to the support; substantially as described.
- 15 2. A manipulator having a transversely movable supporting element, a lifting element having a connection with the supporting element whereby movement imparted to one of the elements will move both elements after an initial independent movement of that element, a motor having an actuating connection with the last named element, and means for holding the other element against movement during a portion of the time of operation of the motor, substantially as described.
- 20 3. A manipulator having a movable support, a tiltable lifter mounted on the support, an actuating motor, connections between the motor and the lifter, connecting means between the lifter and the support, whereby the actuation of the motor will first actuate the lifter to turn the bloom or blank and will then impart a transfer movement to the support, and a friction device acting upon the support to hold it against movement while the lifter is being actuated to turn the bloom or blank, substantially as described.
- 25 4. In a manipulator, a movable support, a lifter pivoted thereto, coöperating means on the lifter and support for causing the lifter to actuate the support after a certain initial movement of the lifter, a motor connected to the lifter, and a holding device arranged to engage said support to permit the support to remain stationary during the initial movement of the lifter, substantially as described.
- 30 5. In a manipulator, the combination of a

movable support, a work engaging member mounted on the movable support having a work engaging portion adapted to be raised and lowered, an actuating motor connected to said member and adapted to impart movement to both the movable member and, by means of said member, to the support, and means between the said member and its support adapted to stop the movement of the said member with relation to said support after a predetermined movement and thereby cause the movement to be imparted to the movable support.

6. In a manipulator, a movable support, a lifter arm pivoted thereto, a holding arm pivoted to the lifter, and a cam surface positioned on the support to be engaged by the holding arm and arranged to move the latter with reference to and upon movement of the lifter arm; substantially as described.

7. A manipulator comprising a movable support, a lifter arm pivoted thereto, a holder arm carried by the lifter arm, a motor connected to the support through the lifter arm, cam means positioned on the support to be engaged by the holding arm to move the latter with reference to and upon movement of the lifter arm and also for locking the lifter arm to the table after an initial independent movement of the lifter arm, and means for resisting the movement of the carriage during the time of independent movement of the lifter arm; substantially as described.

8. In a manipulator, a movable support, a lifter pivoted to said support, a motor connected to the support through the lifter, cam means positioned on the support in position to be engaged by the holding arm and arranged to move the latter with reference to and upon movement of the lifter arm, and a friction device acting upon said support to prevent movement thereof during an initial movement of the lifter arm, substantially as described.

In testimony whereof, I have hereunto set my hand.

FLORENCE C. BIGGERT, JR.
